UNITED STATES PATENT OFFICE.

CHARLES A. DIETZ AND HARRY SCHUMAN, OF NEWARK, NEW JERSEY.

DESIGN FOR A FINGER RING.

Application filed November 11, 1924. Serial No. 11,347. Term of patent 7 years.

To all whom it may concern:

Be it known that we, CHARLES A. DIETZ and HARRY SCHUMAN, citizens of the United States, residing at Newark, in the county of Essex and State of New Jersey, have invented a new, original, and ornamental Design for a Finger Ring, of which the following is a specification, reference being had to the accompanying drawing, forming part thereof.

Figure 1 is a side elevation, and Fig. 2 is an edge view of a finger ring embodying our design.

We claim:

The ornamental design for a finger ring as shown.

CHARLES A. DIETZ.
HARRY SCHUMAN.

Witness:

SAMUEL R. DONCHI.
